(57) **CLAIM**

We claim the ornamental design for a saw blade, as shown and described.

DESCRIPTION

FIG. 1 is a side view of a portion of a saw blade according to an embodiment of the invention.

FIG. 2 is an end view of the portion of the saw blade shown in FIG. 1.

FIG. 3 is a top view of the portion of the saw blade shown in FIG. 1; and,

FIG. 4 is a bottom view of the portion of the saw blade shown FIG. 1.

The elements shown in broken lines are included for the purpose of illustrating environment and form no part of the claimed design. The portions shown in broken lines having unequal length segments illustrate the boundary of the claimed design and form no part of the claimed design.
